United States Patent [19]

Berry et al.

[11] Patent Number: Des. 320,684

[45] Date of Patent: ** Oct. 8, 1991

[54] AUTOMATIC PRINTED CIRCUIT BOARD HANDLER

[75] Inventors: James E. Berry, Fort Collins; Ronald K. Kerschner; Lisa M. Kent, both of Loveland, all of Colo.

[73] Assignee: Hewlett-Packard Co., Palo Alto, Calif.

[**] Term: 14 Years

[21] Appl. No.: 227,278

[22] Filed: Aug. 2, 1988

[52] U.S. Cl. D34/29

[58] Field of Search ..... D34/29; D14/217; 324/158 P, 158 F

[57] CLAIM

The ornamental design for an automatic printed circuit board handler, as shown and described.

DESCRIPTION

FIG. 1 is a perspective view of an automated printed circuit board handler showing my new design;
FIG. 2 is a bottom plan view thereof;
FIG. 3 is a front elevational view thereof;
FIG. 4 is a right side elevational view thereof;
FIG. 5 is a left side elevational view thereof;
FIG. 6 is a rear elevational view thereof;
FIG. 7 is a top plan view thereof.
